ROLLING MACHINE

Alton H. Lundius, South Orange, N. J., assignor to
 General Motors Corporation, Detroit, Mich., a
 corporation of Delaware

Application April 2, 1940, Serial No. 327,389

16 Claims. (Cl. 80—18)

This invention relates to rolling machines and more especially to machines for operating on the ends of elongated articles to upset them. In some roller bearing applications it is considered desirable to use cylindrical rollers which have their ends rounded or convex instead of flat. It is an object of this invention, accordingly, to provide improved mechanism for rounding the ends of cylindrical bearing rollers and other elongated articles.

To these ends and also to improve generally upon machines of this character, the invention consists in the various matters hereinafter described and claimed. In its broader aspects, the invention is not necessarily limited to the specific machine selected for illustrative purposes in the accompanying drawings in which

Fig. 1 is a plan view with some parts broken away and in section.

Fig. 2 is a front elevation of Fig. 1, some parts being broken away and in section.

Fig. 3 is a side elevation of Fig. 1.

Fig. 4 is a vertical section at the drive shaft.

Fig. 5 is a sectional view taken on the line V—V of Fig. 1 some parts being shown in elevation.

Fig. 6 is a sectional view taken principally in the plane of line VI—VI of Fig. 1.

Fig. 7 is an isometric view of the strippers.

Figs. 8 and 9 are isometric views of a plunger.

Fig. 10 is an isometric view of a feed plate.

Fig. 11 is an isometric view of an arm.

Fig. 12 is a sectional view, greatly enlarged, of portions of the die roll and the cage, an article being indicated by broken lines.

Fig. 13 is an isometric view of a portion of the cage.

Fig. 14 is a plan view of the shoe.

Fig. 15 is a side view of the shoe with portions broken away and in section.

Fig. 16 is an isometric view of the feed mechanism, with parts broken away and in section.

Fig. 17 is an isometric view of a rolled article.

Outlining first the general operation, cylindrical rollers are fed one by one to the machine and rolled between a rotating die roll and a curved shoe, the rollers being gradually forced towards the axis of the die roll by the shoe and the die roll having formed or shaped surfaces which engage the ends of the rollers to upset and shape them to a rounded form. The rollers are kept from cocking or getting out of alignment with the die roll by a rotary cage. The upsetting increases the diameter of the rollers near the ends but this excess material is afterwards re-

moved, as by centerless grinding, thus producing cylindrical rollers with rounded or convex ends.

The machine frame comprises a base 2 having a pair of spaced standards 4 and 6. The standard 4 has a recess receiving the outer race ring 8 of a tapered roller bearing 10 whose inner race ring 12 is clamped by a nut and a washer on a drive shaft 14. The standard 4 has a grease fitting 10 while a bolted-on cover plate 16 engages and clamps the end of the race ring 8. The other standard 6 has a recess receiving the outer race ring 18 of a second tapered roller bearing 20 whose inner race ring 22 is clamped against a shoulder on the shaft 14. The roller bearings oppose one another and the end of the race ring 18 is engaged by a bolted-on cover plate 24 having a grease seal 26. Spacing rings 28 engage the two inner race rings and are each surrounded by a grease seal 29.

A die roll is keyed to the drive shaft 14, the roll being formed in spaced sections 30 clamped against an interposed spacing ring 31 (Fig. 4) by screw bolts 32. The peripheries of the sections have mating recesses forming an article receiving space with tapering sides 33 (Fig. 12) leading to curved surfaces 33A adapted to engage the end faces of elongated articles A and roll or upset the end portions to the desired shape. These surfaces converge or taper towards the center of the die roll and are spaced apart axially of the roll. A circular cage 34 has its extended sides 35 journaled with a running fit at 36 on the adjacent spaced apart, cylindrical ends of the sections 30. The cage also has an integral, internal flange or centering tongue 37 which runs freely between the sections and around the spacing ring 31. The outer periphery of the cage has a series of radially open pockets or notches 38 to receive the articles A sideways, these notches being round at the bottom and extending partially into the centering tongue 37. The sides of the notches are straight and terminate at inclined cam faces 39 which, as will appear, control the introduction of the articles. At the bottom of the cage, its outer and somewhat narrowed periphery has a running fit in a central groove 40 of a die plate or shoe 42 which has a curved upper work engaging surface 44 interrupted only by the groove. The interrupted surface 44 is knurled as indicated in Fig. 14 and engages the peripheries of the articles near the ends. As shown in Fig. 2, the shoe 42 has its bottom inclined and supported on a tapered gib or wedge 46 which is adjustable endwise by set screws 48, thereby pro-

viding means to raise or lower the shoe slightly with respect to the die roll. The shoe has a short horizontal adjustment and is clamped by inclined set screws 50 threaded in end plates 52 which are secured by bolts 53 across the standards, the screws 50 engaging inclined surfaces on the shoe to hold the latter down.

The curved surface 44 is a smooth curve conveniently composed of a series of three merging arcs. The central arc has a radius B whose center C is in the axis of the drive shaft 14 and this arc extends from approximately 30° to the left of the vertical to a point approximately 51° to the right of the vertical. It merges at the left with an arc which has a radius E which is a little longer than B and has its center slightly above the center C. The center arc merges at the right with an arc also having a radius E but having its center slightly higher than the other two centers. The knurling extends all the way along the left hand arc and part way along the center arc. At the left and in the center of the width of the shoe, there is a small entrance arc 54 of small radius where the articles enter between the shoe and the die roll sections, this arc merging with the groove 40. The above distances and centers are given by way of illustration and not as limitations. The curved shoe affords a means to make the die roll take hold of the work with a gradually increasing pressure which stays at a maximum and then fades out as the work is discharged at the right. As the work rolls along the shoe, the shoe causes it to approach the axis of the die roll, thus pressing the ends of the work against the shaped surfaces of the die roll sections. The shoe could have a single arcuate surface eccentric to the die roll axis.

Surrounding the upper part of the die roll and the cage is a curved arm 60 which is pivoted on a shouldered stud 62 threaded in the standard 6. The arm has a lubricant port leading to a fitting 64 and its end is forked or divided as at 65. One branch has an opening 66, a portion of which is tapped to receive threads near the pilot end of a locking screw 68 whose body portion turns in a hole in the standard 6 and is operated by a hand wheel 70. The locking screw holds the arm in position but can be retracted to release the arm and permit raising it for access to the cage, die roll and shoe. The other branch of the forked arm 60 has an enlargement with a hole 71 in line with a tapped hole 73 in the first branch to receive a pivot stud 72 for a trigger lever 74 which is urged in one direction by a coil spring 76. The lever has an inclined tooth or cam follower 78 which is hardened and adapted to successively enter the notches 38 in the cage 34 and to be actuated by the inclined cam faces 39 on the cage as the latter rotates. This is a part of the work inserting mechanism as will appear.

The lever 74 carries a pivot stud 80 for a depending bent arm 82 which is adjustably secured by a screw 84 and a cooperating screw 85 to an extension 86 on the lever. The arm 82 has a horizontal feed finger or pusher 88 extending under the extension 86 and entering a groove 90 in the top of a plunger 92. The groove has an unbroken side wall 94 on one side by which the articles are stopped and located endwise when the finger 88 is retracted by the rotation of the cage. The other side wall of the plunger is cut out at 96 to allow the work to come in endwise over the top of the plunger and against the locating side wall 94

5 which extends substantially radially of the die roll. The plunger 92 is urged towards the cage by a coil spring 98 but movement is limited by a stop pin 100. The spring is housed in the plunger and abuts against a wall in a guide plate 102 which has a groove 104 to guide the plunger. The guide plate is held by screws on the standards 4 and 6 and has its upper surface provided with a horizontal feed slot or guide 108 through which the work is fed endwise. The slot is closed at the top by a cover plate 110 extending out to an enlargement 112 on the plate 102, the enlargement having a bore or hole to receive the end of a feed tube on any suitable feed mechanism through which the articles are urged endwise in a stream. At the right of Fig. 2, a pair of pointed strippers 113 spaced by a plate 114 are clamped against a block 116 by a clamping plate 118 having a clamping screw 120 extending through all of said members and into the standard 6 which has a groove to receive a locating tongue 122 on the block 116. Dowel pins 124 locate the strippers on the clamping members. The strippers straddle the high part of the cage and have each a narrow face curved to conform to the die roll sections.

In operation, the articles, such as cylindrical bearing rollers having flat ends are urged by any suitable feeder through the feed slot 108, the foremost article entering endwise through the cut-out 96 in the plunger 92 and engaging its side wall 94. This occurs as the feed finger or pusher 88 is withdrawn by the action of the tooth 78 and the inclined cam faces 39 on the frictionally driven cage. When the tooth 78 drops into a cage notch, the spring 76 urges the feed finger or pusher 88 forwardly against the article to push the latter sidewise into a cage pocket and into the mating recesses of the die roll sections 30. The article is carried downwardly by the cage and is first rolled between the die roll and the end of the plunger 92, the latter yielding as the article rolls by and enters the space between the die roll and the shoe 42. The yielding plunger acts to guide the articles inside of the shoe. Here a gradually increasing pressure due to the diminishing space causes the ends of the articles to press against the shaped walls of the die roll sections, the articles being squeezed also against the knurled surface of the shoe which facilitates rotation rather than sliding. Once an article rolls between the die roll sections and the shoe, the cage is compelled to rotate positively by the translation of the articles. To insure insertion of a first roller so that operation will thereafter be automatic, the rotation of the cage can be manually assisted for a fraction of a revolution. The rolling articles cause the cage to rotate at half the speed of the die roll. The pressure on the articles increases, is then maintained and finally is relieved as the articles approach the discharge end of the shoe. Here the strippers 113 cam the articles away from the die roll and into a suitable receptacle. The articles come out as cylinders with enlarged ends which are substantially spherical segments as indicated in Fig. 17. When the excess diametrical material is removed as by grinding, the articles become 60 cylindrical with rounded ends.

I claim:

1. In a machine of the character indicated, a die roll having shaped surfaces spaced apart axially of the roll and sloping in opposite directions to engage the end faces of elongated arti-

cles, a rotary cage between the surfaces and having a series of pockets to receive articles, a pusher for pushing the articles sideways into the pockets, a lever supporting the pusher and having a cam follower, the cage having cam surfaces to actuate the follower, a shoe having a curved surface along the periphery of the die roll, and means for rotating the roll and the cage.

2. In a machine of the character indicated, a die roll, a shoe having a curved surface along the periphery of the roll, a rotary cage having article-receiving pockets open radially, means for rotating the roll and the cage, a pivoted lever having a pusher movable radially of the cage to push the articles sideways into the radially open pockets, and the pockets having means for actuating the lever.

3. In a machine of the character indicated, a die roll, a shoe having a curved surface along the periphery of the roll, a rotary cage having article receiving pockets open radially, means for rotating the roll and the cage, a pusher for pushing the articles radially into the pockets, and a yielding plunger between the pusher and the shoe to guide the article inside of the shoe.

4. In a machine of the character indicated, a die roll, a shoe having a curved surface along the periphery of the roll, means for rotating the roll, a plunger at one end of the shoe, means for urging the plunger substantially radially towards the roll, and means for introducing elongated rollers between the die roll and the plunger.

5. In a machine of the character indicated, a die roll, a shoe having a curved surface along the periphery of the roll, means for rotating the roll, a plunger at one end of the shoe, means for urging the plunger towards the roll, the plunger having a side wall to locate elongated articles endwise, and a pusher for moving the articles sideways towards the roll.

6. In a machine of the character indicated, a die roll, a shoe having a curved surface along the periphery of the roll, means for rotating the roll, a member having a groove with side wall extending substantially radially of the roll to locate elongated articles endwise, and a pusher operating in the groove for pushing the articles sideways towards the roll.

7. In a machine of the character indicated, a die roll, a shoe having a curved surface along the periphery of the roll, means for rotating the roll, a guide plate having means to guide elongated articles endwise substantially parallel to the axis of the roll, a yieldable plunger having a side wall to locate the articles endwise, and a pusher adapted to move lengthwise of the plunger to push the articles sideways towards the roll.

8. In a machine of the character indicated, a die roll, a shoe having a curved surface along the periphery of the roll, a curved arm overlying another portion of the periphery of the roll, a pusher having a pivotal mounting on the arm for urging elongated articles towards the roll, and the arm having a pivot to provide for lifting said pusher and exposing the roll.

9. In a machine of the character indicated, a die roll, a shoe having a curved surface along the periphery of the roll, a curved arm overlying another portion of the periphery of the roll, a yieldable plunger between the shoe and the end of the arm, a pusher on the arm, and the arm having a pivot to provide for swinging the pusher away from the plunger.

10. In a machine of the character indicated, a die roll, a shoe having a curved surface along the periphery of the roll, means for introducing elongated articles between the roll and the shoe at one end of the latter, a cage having pockets for the articles to guide them between the roll and the shoe, and strippers at the other end of the shoe and straddling a portion of the cage for removing the articles.

11. In a machine of the character indicated, a die roll having shaped surfaces spaced apart and converging towards the center of the die roll to engage the end portions of elongated rollers, a shoe opposed to the die roll and having a curved surface which gradually approaches the periphery of the die roll, the curved surface having a central groove, a rotary cage extending between the shaped surfaces and having pockets for spacing the rollers, the outer periphery of the cage entering the groove in the shoe, and means for rotating the die roll.

12. In a machine of the character indicated, a die roll having a work receiving space in its periphery, the space having oppositely facing surfaces converging towards the center of the roll to engage the ends of an elongated article and upset the same, the die roll also having spaced apart peripheral surfaces of smaller diameter than the converging surfaces to engage the periphery of the article, a cage turning freely on the peripheral surfaces and having a centering tongue projecting between them, the cage also having article receiving pockets open radially, a shoe curved about the roll, and means for rotating the roll.

13. In a machine for rounding the ends of a cylindrical article by an upsetting operation, a die roll, a shoe having a concave article engaging surface gradually approaching the roll periphery in one direction, the roll having shaped article upsetting surfaces spaced apart axially a distance shorter than the length of the article, said surfaces converging steeply towards the axis of the roll for forcible upsetting contact with the corners at the end faces of the article, and means for advancing the article between the shoe and the die roll to force said corners down the converging surfaces to thereby upset and round the ends of the article.

14. In a machine for rounding the ends of elongated articles by an upsetting operation, a rotary die roll having shaped article upsetting surfaces spaced apart axially of the roll a shorter distance than the length of the article, said surfaces converging steeply towards the axis of the roll for forcible upsetting contact with the corners at the end faces of the article, a rotary cage between the converging surfaces and having article pockets, and a shoe having a concaved article engaging surface gradually approaching the roll periphery in one direction for forcing said corner down the converging surfaces to upset the ends of the article as the article is rollingly advanced between the roll and the shoe.

15. In a machine for rounding the ends of a cylindrical article by an upsetting operation, a die roll, a shoe having a concave article engaging surface gradually approaching the roll periphery in one direction, the roll having shaped article upsetting surfaces spaced apart axially a distance shorter than the length of the article, said surfaces converging steeply towards the axis of the roll for forcible upsetting contact with the corners at the end faces of the article, a rotary cage between the converging surfaces and

having pockets to receive the article, a pusher for pushing the articles sideways into the pockets, means for causing the rotation of the cage to actuate the pusher, and means for rollingly advancing the article between the shoe and the die roll to force said corners down the converging surfaces to upset the ends.

16. In a machine for rounding the end of a cylindrical article by an upsetting operation, a die roll, a shoe having a concave article engaging surface gradually approaching the roll periphery

5 in one direction, the roll having a curved upsetting surface sloping steeply towards the axis of the roll for forcible upsetting contact with the corner at the end face of the article, a co-operating opposing surface on the die roll to take the endwise reaction, and means for rotating the roll to advance the article between the shoe and the die roll and thereby force said corner down the sloping surface to upset and round the end

10

ALTON H. LUNDIUS.
